MANUFACTURE OF CIGARETTES

Adolf Bernd, London, England, assignor to Filter
Tips Limited, London, EnglandApplication February 2, 1937, Serial No. 123,690
In Great Britain February 5, 1936

26 Claims. (Cl. 131—94)

This invention relates to the manufacture of cigarettes and is particularly concerned with improvements in the manufacture of filter tip cigarettes by uniting axially aligned cigarettes or lengths of cigarette rod and filter tips or mouthpiece portions by means of external uniting bands of cork or other suitable material.

The invention has for its object to provide an improved method for effecting the wrapping of the uniting bands around the aligned lengths without such lengths undergoing any axial or rotary movement, further to provide apparatus for carrying out the method referred to whereby the uniting of the aligned lengths may be effected with precision and certainty at a comparatively high rate of output, and generally to provide improvements in method and apparatus whereby the manufacture of filter tip cigarettes may be carried out economically and expeditiously.

The invention is hereinafter described by way of example with reference to the accompanying diagrammatic drawings, in which:

Figure 1 is a view in side elevation partly in section illustrating one embodiment in accordance with the invention;

Figure 2 is a prespective view drawn to an enlarged scale illustrating the construction and manner of operation of the axially moving 30 wrapping device shown in Figure 1;

Figure 3 is a sectional view taken on line 3—3 of Fig. 4 illustrating a modification;

Figure 4 is a sectional plan of the wrapping mechanism shown in Figure 3 and taken on line 35 4—4 thereof; and

Figure 5 is a fragmentary sectional view taken on line 5—5 of Fig. 1.

Fig. 6 is a plan view of that part of the apparatus shown in Fig. 5.

Fig. 7 is a detail plan view of one of the wrapping mechanisms in an intermediate position taken on a plane perpendicular to the radius of the carrier 19.

In carrying the invention into effect according 45 to one embodiment and with reference to Figures 1 and 2 of the accompanying diagrammatic drawings, pairs of cigarettes 1 with interposed filter tips 2 or other mouthpiece portions are fed axially into a channel-shaped member 3, the lengths having been previously assembled by suitable known means. The member 3 is carried on a lever 3a pivoted at 3b and provided with a roller 3c which co-operates with a cam 4a on a main driving shaft 4, a return spring 3d being provided.

Under the influence of the cam 4a the member 3 is moved towards a suction arm 5a on a rotary suction drum 5 which is moved intermittently by the engagement of a gear segment 6 with a gear wheel 5b attached to the drum 5 which, during the stationary periods, is locked by means such

as segment 6a of larger diameter than the gear segment 6 co-operating with a stop disc 5c. Suction holes 5d in the arms 5a extend from the concave ends 5e of the arms to a suction chamber 5f which communicates through a hole 5g with a bore 5h in a fixed spindle 5j on which the drum 5 is mounted. A stationary suction cut-off member 5i is provided.

The lengths carried by the member 3 into engagement with the respective suction arm 5a are 10 retained thereon by suction and on the next movement of the drum 5 are carried into contact with the previously pasted band 7 of cork or the like fed on a suction drum 8 in the usual manner, the drum 8 being preferably geared to 15 the drum 5 by the gear 8a meshing with the gear 5b. On the next movement of the drum 5 the aligned lengths with the uniting band 7 attached are carried into a position opposite a channel-shaped member 9. The member 9 is mounted 20 on two sliding spindles 10 mounted in brackets 10a and provided with rollers 10b co-operating with cams 4b on the shaft 4 and with springs 10c by which movement of the member 9 towards the drum 5 is effected. When the member 9 moves 25 the drum 5 it acts to wrap the uniting band 7 around approximately half the circumference of the lengths, as shown in dotted lines. On the next movement of the drum 5 the aligned lengths with the band 7 wrapped half round the same 30 registers with a groove 11a in a second suction drum 11. On the next movement of the drum 5 taking place suction to the respective arm 5a is cut off by the member 5i so that the assemblage 35 comprising the aligned lengths and the uniting band is retained in the respective groove 11a by suction exerted through holes 11b communicating with a suction chamber 11c which in turn communicates through a hole 11d with a bore 11e in a stationary spindle 11g on which the drum 11 is mounted, it being understood that the bores 5h and 11e are connected to a suitable source of suction. The drum 11 may be geared to the drum 5 by means of the gear 11h meshing with the gear 5b. On the drum 11 the assemblies 40 are carried to a position at which a wrapping device reciprocatable in a direction parallel with the axis of the drum 11 is provided. This wrapping device may be of any suitable construction and, as shown in the drawings, it may 45 consist of two suitably shaped wrapping members 12a, 12b mounted on pins 12c fixed to a member 12d provided with rollers 12e running in guides 12f, the member 12d being reciprocated, for instance, by a conventional crank drive (not shown) connected to a link 12g. During the 50 movements of the drum 11 the wrapping device is disposed beyond one end or the other of the drum and while the drum 11 is stationary the wrapping device 12 moves axially along the as- 55 60

semblage, as shown in Figure 2, and eventually it passes clear of the drum at the other end thereof. The drum 11 then moves forward a step and on the return movement of the wrapping device it passes along the next assemblage on the drum 11, the members 12a, 12b, being shaped so as to have the desired wrapping action on the band 7 in either direction of movement. If desired, the assemblage may be positioned on the drum 11 by means such as stops 11c (Figure 2) serving to prevent any possibility of axial movement of the assemblage while the wrapping device is acting thereon.

The united assemblages are carried on the drum 11 step by step to a discharge point at which they are delivered on to a conveyor such as a belt 15 passing over a roller 15a. A rotary cutter 14 operated in known manner may act to bisect the assemblages prior to their discharge, 20 in which case means such as fixed guides 13 may be provided to hold the assemblages firmly in the grooves 11a during the cutting operation.

In a modification, as illustrated in Figures 3 and 4, the assemblages are delivered to the suction arms 5a of the suction drum 5 as before described by a drum 16 having grooves 16a which receive the lengths from hopper or other feeding means, the lengths being retained in the grooves 16a by means of fixed guides 17 extending 30 up to the point at which the lengths are transferred to the suction arm 5a. In this embodiment the drums may move continuously and the drum 16 may be geared to the drum 5 by means of the gear 16b meshing with the gear 5b. The assemblage received on the suction arm 5a is carried into contact with the uniting band 7 fed on a suction drum 8 as before described, such drum 8 being geared to the drum 5 by the gear 8a meshing with the gear 5b. The assemblage with the 40 uniting band 7 attached thereto is then acted on by a rotary member 18 having grooves 18a which act to press the uniting band 7 around approximately half the circumference of the assemblage, the member 18 being geared to the drum 5 by means of the gear 18b meshing with the gear 5b. The assemblage is then carried to a position at which it registers with a groove 19h in a suction member 19a mounted on a carrier 19 and at this position the assemblage is transferred by suction 50 from the suction arm 5a to the member 19a.

As shown, the carrier 19 is provided with a series of suction members 19a which at their outer ends may be supported by and attached to an end plate 19e (Fig. 4). Each member 19a is 55 provided with a bore 19b communicating through holes 19c with the groove 19h and through a hole 19d with a suction chamber 19e which in turn communicates through holes 19f and 20a with a bore 20b in a fixed spindle 20 on which the carrier 19 is rotatable. The suction to the members 19a is controlled by a fixed suction cut-off member 22a carried by an end plate 22 which is fixed to the stationary spindle 20. The spindle 20 may be mounted in supporting brackets 21.

65 As the assemblages are carried around on the members 19a they are acted on by wrapping devices 23 moving axially along the assemblage so that thus the wrapping of the uniting band around the assemblage is effected by axially moving 70 means while the assemblage is being carried laterally and without any rotation of the assemblage. Each wrapping device may consist of a substantially U-shaped member slidably mounted on cross bars 24 and arranged to encircle the respective 75 member 19a, the ends of the member 23 being

provided with suitably shaped wrapping members 23b, 23c similar to the members 12a, 12b shown in Figure 1. Inasmuch, however, as in this embodiment the wrapping is always effected by axial movement in the one direction, the wrapping members 23b, 23c are of only half the length of the members 12a, 12b. The movement of the device 23 along the assemblage is effected, for instance, by the provision of a roller 23a on the device 23 engaging a cam groove 25a in a cylinder 10 25 fixedly mounted on the stationary shaft 20.

At the discharge position where the completed assemblage is delivered on to a conveyor belt 15, the suction is cut off by the member 22a and at the same time compressed air may be admitted 15 from a pipe 26 through a hole 22b in the end plate 22 registering with the bore 19b, as shown in Figure 4, so as to blow the assemblage out of the groove 19h on to the belt 15, suitable guides 27 being provided to ensure the proper position- 20 ing of the assemblage on the belt 15.

It will be understood that the mechanism hereinbefore described may be modified in various ways without departing from the invention. Furthermore, the invention is applicable for uniting single cigarette lengths and single filter tips or mouthpiece portions and also for uniting assemblages comprising more than three parts, in which case more than one uniting band will be applied to each assemblage. 30

The invention is applicable to the production of composite cigarettes containing two different kinds of tobacco.

I claim:

1. A method for the manufacture of filter tip cigarettes by uniting lengths of cigarette rod and of mouthpiece filling by means of external bands, comprising feeding an assemblage comprising the lengths to be united to a conveyor carrying the assemblage laterally on said conveyor into contact with a uniting band, transferring the assemblage with the uniting band attached to a second conveyor, lapping the uniting band around part of the circumference of the assemblage and completing the wrapping of the uniting band 45 around the assemblage by displacing a wrapping device parallel to the axis of said assemblage. 40

2. Apparatus for the manufacture of filter tip cigarettes, comprising a conveyor, on which assemblages of lengths of cigarette rod and of mouthpiece filling are carried laterally, means for positioning the said assemblages on the conveyor, and wrapping means movable axially along the assemblages while positioned on the said conveyor. 50

3. Apparatus as claimed in claim 2, wherein the axially moving wrapping means is associated with each positioning means on the said conveyor, and further comprising actuating rollers on said wrapping means and mechanism for moving the 60 said wrapping means axially during movement of the said conveyor, said mechanism comprising a stationary cam co-operating with the rollers on the said wrapping devices. 55

4. Apparatus as claimed in claim 2, wherein the axially moving wrapping means is associated with each positioning means on the said conveyor and mechanism is provided for moving the said wrapping means axially during movement of the said conveyor, the said conveyor being provided with suction means for positioning the assemblages thereon and with means of cutting off the suction and for admitting compressed air to effect removal of the assemblage from the said conveyor at the discharge point. 65

5. Apparatus for the manufacture of filter tip cigarettes, comprising an intermittently moving conveyor, suction means on said conveyor for positioning assemblages of lengths of cigarette rod and of mouthpiece filling, means for feeding the assemblages to the said suction means, mechanism for bringing previously pasted uniting bands into contact with the assemblages positioned on the said conveyor, means acting in a direction approximately perpendicular to the axis of each assemblage to wrap the uniting band substantially half round the same, a second intermittently moving conveyor arranged to receive the assemblages with the uniting band partly wrapped therearound, and an axially movable wrapping device arranged to move axially along each assemblage while said second conveyor is stationary to complete the wrapping of the uniting band around the assemblage. 10
20. 6. Apparatus as claimed in claim 5, wherein the wrapping device comprises folding members operating to wrap the uniting band around the assemblage in either direction of movement of the wrapping device, the movement of the wrapping device in relation to one assemblage being opposite to the movement in relation to a preceding assemblage. 20
7. Apparatus for the manufacture of filter tip cigarettes comprising a continuously moving wrapping conveyor, a continuously moving conveyor by which assemblages of lengths of cigarette rod and of mouthpiece filling are fed to said continuously moving wrapping conveyor, means for bringing previously pasted uniting bands into contact with the said assemblages while carried on said first continuously moving conveyor, means acting to wrap uniting bands partially around the assemblages, means for positioning the assemblages on said wrapping conveyor, an axially moving wrapping device associated with each of said positioning means, and mechanism for effecting axial movement of the wrapping devices during the continuous movement of the said wrapping conveyor. 35
45. 8. Apparatus as claimed in claim 7, wherein the wrapping conveyor is of cylindrical formation, and said mechanism comprises a fixedly mounted cylindrical member provided with a cam groove, and means cooperating with said groove for effecting the movement of said axially moving wrapping device. 45
9. A method for the manufacture of filter tip cigarettes by uniting lengths of cigarette rod and of mouthpiece filling by means of external bands, comprising depositing an assemblage of aligned lengths of cigarette rod and of mouthpiece filling on a conveyor, displacing said conveyor for carrying the assemblage laterally, and displacing a wrapping device axially along said assemblage, while on said conveyor, to wrap a uniting band about the assemblage. 55
60. 10. A method for the manufacture of filter tip cigarettes by uniting lengths of cigarette rod and of mouthpiece filling by means of external bands, comprising depositing an assemblage of aligned lengths of cigarette rod and of mouthpiece filling on a conveyor for carrying the same laterally, intermittently displacing said conveyor for carrying the assemblage laterally, and, while the conveyor is stationary between intermittent displacements thereof, displacing a wrapping device axially along said assemblage, while on said conveyor, to wrap a uniting band about the assemblage. 70
75. 11. A method for the manufacture of filter tip cigarettes by uniting lengths of cigarette rod and of mouthpiece filling by means of external bands, comprising depositing an assemblage of aligned lengths of cigarette rod and of mouthpiece filling on a conveyor, displacing said conveyor for carrying the assemblage laterally, and displacing a wrapping device axially along said assemblage, while on said conveyor, to wrap a uniting band about the assemblage while the conveyor is moving. 5
12. A method for the manufacture of filter tip cigarettes by uniting lengths of cigarette rod and of mouthpiece filling by means of external bands, comprising positioning an assemblage of aligned lengths of cigarette rod and of mouthpiece filling together with a uniting band in contact therewith on a conveyor, displacing said conveyor for carrying the assemblage laterally, and displacing a wrapping device axially along said assemblage, while on said conveyor, to wrap the uniting band about the assemblage while the assemblage is being carried laterally. 15
13. A method for the manufacture of filter tip cigarettes by uniting lengths of cigarette rod and of mouthpiece filling by means of external bands, comprising wrapping a uniting band partly about an assemblage of axially aligned lengths of cigarette rod and mouthpiece filling, depositing said partly wrapped assemblage on a conveyor, displacing said conveyor for carrying the partly wrapped assemblage laterally, and displacing a wrapping device axially along said assemblage, while on said conveyor, to wrap the uniting band about the assemblage. 25
14. A method for the manufacture of filter tip cigarettes by uniting lengths of cigarette rod and of mouthpiece filling by means of external bands, comprising effecting a relative displacement between a wrapping device and an assemblage of axially aligned lengths of cigarette rod and of mouthpiece filling in a direction perpendicular to the axis of the assemblage to partially wrap a uniting band about said assemblage, depositing said partially wrapped assemblage on a conveyor, displacing said conveyor for carrying the partially wrapped assemblage laterally, and displacing a wrapping device axially along said assemblage, while on said conveyor, to wrap the uniting band about the assemblage. 35
15. A method for the manufacture of filter tip cigarettes by uniting lengths of cigarette rod and of mouthpiece filling by means of external bands, comprising wrapping a uniting band partly about an assemblage of axially aligned lengths of cigarette rod and of mouthpiece filling, depositing said partly wrapped assemblage on a conveyor, displacing said conveyor for carrying the partly wrapped assemblage laterally, and displacing a wrapping device axially along said assemblage, while on said conveyor, to wrap the uniting band about the assemblage while the assemblage is being carried laterally. 50
16. A method for the manufacture of filter tip cigarettes by uniting lengths of cigarette rod and of mouthpiece filling by means of external bands, comprising effecting a relative displacement between a partial wrapping device and an assemblage of axially aligned lengths of cigarette rod and of mouthpiece filling in a direction perpendicular to the axis of the assemblage to partially wrap a uniting band about said assemblage, depositing said partially wrapped assemblage on a conveyor, displacing said conveyor for carrying the partially wrapped assemblage laterally, and displacing a wrapping device axially along said assemblage, while on said conveyor, to wrap the uniting band about the assemblage while the assemblage is being carried laterally. 65
70. 75. 11. A method for the manufacture of filter tip cigarettes by uniting lengths of cigarette rod and of mouthpiece filling by means of external bands, comprising depositing an assemblage of aligned lengths of cigarette rod and of mouthpiece filling on a conveyor, displacing said conveyor for carrying the assemblage laterally, and displacing a wrapping device axially along said assemblage, while on said conveyor, to wrap a uniting band about the assemblage while the assemblage is being carried laterally. 75

- ially along said assemblage, while on said conveyor, to wrap the uniting band about the assemblage while the assemblage is being carried laterally.
- 5 17. Apparatus for the manufacture of filter tip cigarettes, comprising a conveyor, on which assemblages of lengths of cigarette rod and of mouthpiece filling are carried laterally, means for positioning said assemblages on the conveyor, 10 wrapping means movable axially along the assemblages while positioned on the conveyor, means for moving said conveyor intermittently, and means for displacing said axially movable wrapping means, while the conveyor is stationary, 15 between intermittent movements and for displacing the wrapping means in an opposite direction after each intermittent movement of the conveyor.
18. A method for the manufacture of filter tip 20 cigarettes by uniting lengths of cigarette rod and of mouthpiece filling by means of external bands, comprising conveying an assemblage comprising the lengths to be united laterally into contact with a uniting band along a line intermediate 25 the ends of said band, wrapping the mid-portion of the uniting band partly about the assemblage by pressing the uniting band transversely to the axis of the assemblage symmetrically and simultaneously around the lengths to be united, and 30 completing the wrapping of the uniting band around the assemblage by the application of external lateral pressure progressively along said assemblage to close the ends of the uniting band around it.
- 35 19. A method for the manufacture of filter tip cigarettes by uniting lengths of cigarette rod and of mouthpiece filling by means of external bands, comprising holding an assemblage of aligned lengths of cigarette rod and of mouthpiece filling, conveying said assemblage laterally to a wrapping zone, and wrapping a uniting band around the assemblage, while so held, and while in the wrapping zone, by the application of external lateral pressure progressively along 40 said assemblage to close the uniting band around it.
20. A method for the manufacture of filter tip 45 cigarettes by uniting lengths of cigarette rod and of mouthpiece filling by means of external bands, comprising holding an assemblage of aligned lengths of cigarette rod and of mouthpiece filling, intermittently conveying said assemblage laterally through a wrapping zone, and wrapping a uniting band around the assemblage, 50 while so held, and while in said wrapping zone, during an interval in the conveying, by the application of external lateral pressure progressively along said assemblage to close the uniting band around it.
- 55 21. A method for the manufacture of filter tip 55 cigarettes by uniting lengths of cigarette rod and of mouthpiece filling by means of external bands, comprising holding an assemblage of aligned lengths of cigarette rod and of mouthpiece filling, conveying said assemblage laterally through a wrapping zone, and wrapping a uniting band around the assemblage, while so held and during lateral conveying thereof through said wrapping zone, by the application 60 of external lateral pressure progressively along said assemblage to close the uniting band around it.
- 65 22. A method for the manufacture of filter tip 65 cigarettes by uniting lengths of cigarette rod and of mouthpiece filling by means of external bands, comprising wrapping a uniting band partly about an assemblage of aligned lengths of cigarette rod and of mouthpiece filling, conveying said assemblage laterally through a wrapping zone, and wrapping the uniting band around the assemblage, while so held and during lateral conveying thereof through said wrapping zone, by the application 70 of external lateral pressure progressively along said assemblage to close the ends of the uniting band around it.
- 75 and of mouthpiece filling by means of external bands, comprising holding an assemblage of aligned lengths of cigarette rod and of mouthpiece filling, conveying said assemblage laterally into contact with a uniting band, further conveying said assemblage together with said uniting band in contact therewith through a wrapping zone, and wrapping the uniting band around the assemblage while so held and during lateral conveying thereof through said wrapping zone, by the application of external lateral pressure progressively along said assemblage to close the uniting band around it.
- 80 23. A method for the manufacture of filter tip 80 cigarettes by uniting lengths of cigarette rod and of mouthpiece filling by means of external bands, comprising wrapping a uniting band partly about an assemblage of axially aligned lengths of cigarette rod and of mouthpiece filling, so that the mid-portion of said uniting band partly surrounds said assemblage, conveying said partly wrapped assemblage laterally through a wrapping zone, and completing the wrapping of the uniting band around the assemblage by the application of external lateral pressure progressively along said assemblage to close the ends of the uniting band around it.
- 85 24. A method for the manufacture of filter tip 85 cigarettes by uniting lengths of cigarette rod and of mouthpiece filling by means of external bands, comprising wrapping the mid-portion of a uniting band partly about an assemblage by pressing the uniting band transversely to the axis of the assemblage symmetrically and simultaneously around the lengths to be united, conveying said partly wrapped assemblage laterally through a wrapping zone, and completing the wrapping of the uniting band around the assemblage by the application of external lateral pressure progressively along said assemblage to close 90 the ends of the uniting band around it.
- 95 25. A method for the manufacture of filter tip 95 cigarettes by uniting lengths of cigarette rod and of mouthpiece filling by means of external bands, comprising wrapping a uniting band partly about an assemblage of axially aligned lengths of cigarette rod and of mouthpiece filling, so that the mid-portion of said uniting band partly surrounds said assemblage, conveying said partly wrapped assemblage laterally through a wrapping zone, and completing the wrapping of the uniting band around the assemblage during lateral conveying thereof through said wrapping zone, by the application of external lateral pressure progressively along said assemblage to close 100 the ends of the uniting band around it.
- 105 26. A method for the manufacture of filter tip 105 cigarettes by uniting lengths of cigarette rod and of mouthpiece filling by means of external bands, comprising wrapping the mid-portion of a uniting band partly about an assemblage by pressing the uniting band transversely to the axis of the assemblage symmetrically and simultaneously around the lengths to be united, conveying said partly wrapped assemblage laterally through a wrapping zone, and completing the wrapping of the uniting band around the assemblage during lateral conveying thereof through said wrapping zone, by the application of external lateral pressure progressively along said assemblage to close the ends of the uniting band around it.
